FIG. 4

Fig. 1 is a perspective view of a medical lamp and supporting arm unit, showing the new design. The shading on the bottom of the light member in Fig. 1 indicating a conventional fabric is understood to be repeated throughout;

Fig. 2 is a side elevation thereof;

Fig. 3 is a top plan view thereof; and

Fig. 4 is a view partly in front elevation and partly in vertical section through the lamp head.

I claim:

The ornamental design for a medical lamp and supporting arm unit, substantially as shown and described.
